HEEL FOR FOOTWEAR

Carlo Antoline, Ferriday, La.

Application May 18, 1937, Serial No. 143,301

2 Claims. (Cl. 36—34)

This invention relates to heels for footwear. It is particularly directed to a light weight, long wearing heel for men's and women's shoes or slippers.

5 An object of this invention is to provide a heel of the character described, so constructed as to allow nails to be driven in without splitting, and which shall be extremely light and strong.

A further object of this invention is to provide a heel of the character described made of 10 layers of wood and leather, or rubber, and which shall be strong and rugged in construction, and easy to make.

15 Yet another object of this invention is to provide a heel of the character described which shall be relatively inexpensive to manufacture, and yet practical and efficient to a high degree in use.

Other objects of this invention will in part be 20 obvious and in part hereinafter pointed out.

The invention accordingly consists in the features of construction, combinations of elements, and arrangement of parts which will be exemplified in the construction hereinafter described, and of which the scope of application will be 25 indicated in the following claims.

In the accompanying drawing, in which is shown one of the various possible illustrative embodiments of this invention,

Fig. 1 is a side elevational view of a heel embodying the invention, with parts in cross-section; and

Fig. 2 is a bottom plan view of my improved heel, with parts broken away.

Referring now in detail to the drawing, 10 designates a heel embodying the invention applied to a shoe or slipper 11. The heel 10 comprises a lift layer 12 of leather or rubber, a tread layer 13 of leather or rubber, and an intermediate layer or portion 14 of wood. The strips of leather or rubber may be adhered to opposite faces of the wood part 14, by glue or in any other suitable manner as at 18 and 19. Furthermore nails 20 may be driven through the leather and wood to hold the same together, and for the purpose

of attaching the same to the shoe or slipper. The part 14 is preferably considerably thicker than the leather layers 12 and 13.

The wood part 14 is preferably made of cypress knee wood. The cypress knee wood grows from 5 the root of the cypress tree, and extends above the ground. This wood not having a decided grain allows the nails to be driven without causing the wood to split. This wood is much lighter than the usual cypress wood, and has been found 10 to be extremely efficient for the purposes above set forth. The leather portions 12, 13 are preferably oak tanned.

The combination in a heel of leather or rubber and wood produces a heel having extremely long 15 wearing quality. Such a heel is rugged, practical and efficient.

The heel can be made in any size or shape. The invention may be incorporated in heels for 20 shoes for either men or women. The heel is extremely cheap to fabricate and will not split even if a considerable number of nails are driven into it.

It will thus be seen that there is provided a device in which the several objects of this invention are achieved, and which is well adapted to 25 meet the conditions of practical use.

As various possible embodiments might be made of the above invention, and as various changes might be made in the embodiments set 30 forth, it is to be understood that all matter herein set forth or shown in the accompanying drawing is to be interpreted as illustrative and not in a limiting sense.

Having thus described my invention, I claim 35 as new and desire to secure by Letters Patent:

1. A shoe heel having an intermediate major part made of cypress knee wood and tread and lift layers of leather on opposite sides of said part.

2. A shoe having a heel comprising a major part made of cypress knee wood, and a tread attached thereto.

CARLO ANTOLINE.
